UNITED STATES PATENT OFFICE.

EDWARD WALSH, JR., OF ST. LOUIS, MISSOURI.

DESIGN FOR SHEET-GLASS.

SPECIFICATION forming part of Design No. 34,845, dated July 23, 1901.

Application filed July 1, 1901. Serial No. 66,785. Term of patent 14 years.

To all whom it may concern:

Be it known that I, EDWARD WALSH, Jr., a citizen of the United States, residing at the city of St. Louis, in the State of Missouri, have 5 invented a certain new and original Design for Sheet-Glass, of which the following is a full, clear, and exact description, such as will enable others skilled in the art to which it applies to make and use the same, reference 10 being had to the accompanying drawings, forming part of this specification, in which—

Figure 1 is a plan view of a portion of a sheet of glass made in accordance with my new and original design, said view representing the reverse side thereof. Fig. 2 is a similar view representing the obverse side, and Fig. 3 is an edge elevational view.

This invention relates to a new and original design for sheet-glass; and it consists in the 20 surface ornamentation thereof, as will hereinafter be more fully described.

In the drawings I have shown a portion of a sheet of glass, one surface of which I have designated as the "obverse" side being configured by parallel rounded corrugations, while the opposite or reverse side of the sheet 25 is configured by raised and depressed portions, forming a roughened surface resembling broken granite.

30 The design consists, essentially, of an irregu-

lar surface resembling in appearance the surface of granite as it would appear after a fracture. This surface is formed by numerous facets of irregular size, shape, and angularity with respect to each other, all of said 35 facets being closely grouped together, as shown in the drawings.

A sheet of glass ornamented and configured according to my new and original design has an appearance to the observer different from 40 either of the designs on the opposite faces thereof. When the corrugated surface is nearest the observer, the regularity of the surface resembling broken granite on the reverse side is destroyed by refraction, so that the 45 convexes of the corrugations are traversed by light and shades at about right angles to the axes thereof, while in the concaves of the corrugations the roughened surface resembling broken granite is better defined. 50

What I claim is—

The design for sheet-glass, substantially as herein shown and described.

In testimony whereof I hereunto affix my signature, in the presence of two witnesses, 55 this 21st day of June, 1901.

EDWARD WALSH, JR.

Witnesses:

GEORGE BAKEWELL,
F. R. CORNWALL.
